UNITED STATES PATENT OFFICE.

MARCELLA HAMILTON GOODRICH, OF BALTIMORE, MARYLAND, ASSIGNOR
TO ANTON H. FETTING, OF BALTIMORE, MARYLAND.

DESIGN FOR A BADGE.

No. 38,582.

Specification for Design.

Patented May 28, 1907.

Application filed April 27, 1907. Serial No. 370,730. Term of patent 14 years.

To all whom it may concern:

Be it known that I, MARCELLA HAMILTON GOODRICH, a citizen of the United States, residing at Baltimore city, in the State of Maryland, have invented a certain new, original, and ornamental Design for a Badge, of which the following is a specification, reference being had to the accompanying drawing, forming part thereof.

The figure is a perspective view of a pin-badge, showing my new design.

What I claim is:—

The ornamental design for a badge, as shown.

MARCELLA HAMILTON GOODRICH.
